UNITED STATES PATENT OFFICE.

DAVID SWOPE, OF MERCHANTVILLE, NEW JERSEY.

CLAMP.

No. 833,945.

Specification of Letters Patent.

Patented Oct. 23, 1906.

Application filed March 16, 1906. Serial No. 306,337.

To all whom it may concern:

Be it known that I, DAVID SWOPE, a citizen of the United States, residing at Merchantville, Camden county, State of New Jersey, have invented a new and useful Clamp, of which the following is a specification.

My invention relates to a novel construction of a clamp for stretching hides or skins, which is adapted to be employed in place of the toggle which is ordinarily used in the stretching operation, wherein it is necessary to perforate the hides along their edges in order that the toggle-strings may be passed therethrough, by means of which the hide is suitably secured to the frame.

In a prior patent, No. 790,012, granted to me May 16, 1905, I have described and claimed a novel construction of a clamp which can be readily applied to the hide and which is so constructed that the pull on the clamp will stretch the hide and more tightly clamp the same.

It has been found in practice that under certain conditions when a great pressure is exerted on the clamp there is a liability, if comparatively thin metal is employed, of the sides of the clamp springing or spreading apart, and thus permitting the internal clamping member to be partially disengaged therefrom, and thereby lessening the strength of the clamping action. In my present invention I have overcome this defect caused by the spreading of the sides which sometimes occurs, and to the above end my present invention consists of a novel construction of a clamp comprising two clamping members, the sides of the outer member each having a slot therein in which the journals of the internal member are seated; said journals being provided with a lug, whereby when the parts are in assembled position there is no possibility of the sides spreading or bending outwardly under the strain, and, furthermore, the two clamping members may be readily assembled and disassembled when desired.

It further consists of a novel construction of clamping members in which the sides of the outer member are provided with slots in which the internal member when in unclamped position has a desired amount of play and when the different members are in clamped position the journals of the internal member engage the upper ends of the slots in the sides of the outer member.

It further consists of other novel features

of construction, all as will be hereinafter fully set forth.

Figure 1 represents a plan view of a clamp embodying my invention, the same being shown as the parts appear after being stamped from the sheet metal and before the sides and clamping-jaws have been deflected into the proper position. Fig. 2 represents a perspective view of the clamp in assembled position, showing a flexible connection in operative position with respect thereto. Fig. 3 represents a side elevation of Fig. 2. Fig. 4 represents a perspective view of another embodiment of my invention. Fig. 5 represents a plan view of the internal clamping member shown in Fig. 4.

Similar numerals of reference indicate corresponding parts in the figures.

Referring to the drawings, 1 designates a novel construction of a clamp embodying my invention, the same consisting of an outer or external member 2, having sides 3 rising therefrom, between which the internal clamping member 4 is detachably secured. The outer member 2 is provided with forward extensions terminating in a clamping-jaw 5, with which the clamping-jaw 6, forming a termination of the forward extension of the internal member 4, is adapted to coact. The sides 3 of the outer member are provided with slots 7, shown as though not necessarily substantially vertical, in which the journals 8 of the internal member 4 are adapted to be seated, said journals having at their ends the lugs or bars 9, which are of the same length or slightly shorter than the slots 7 in the sides 3, whereby the internal member of the clamp may be readily assembled or disassembled whenever it is desired, and the internal member will be permitted to have a desired amount of vertical play within the sides 3 of the external member 2. The internal member 4 has extending rearwardly therefrom the finger-piece or rearward extension 10, having an aperture 11 therein, through which passes the flexible connection 12, said connection also passing through an aperture 13 in the finger-piece or rearward extension 14 of the outer member 2. In the present instance the flexible connection is shown as passing through the aperture 11 and having a knot at its end, although it will be apparent that this flexible connection may be secured with respect to the finger-pieces 10 and 14 in any desired manner.

In the embodiment seen in Figs. 4 and 5 I

have shown a different construction of an internal member, although the action of the clamp will be precisely similar to that already described in the embodiment shown in Figs. 1 to 3, inclusive. In this embodiment the journals 8 have at their outer end a lug 15, one end of which is substantially flush with the end of the journal and extends therefrom in only one direction. In the present instance I have shown this lug as extending rearwardly, although it will be apparent that the same may be extended forwardly instead of rearwardly and still be within the scope of my invention.

15 My present invention, with the exception of the slots in the sides and the lugs or bars 9 or 15 at the end of the journals of the internal member, is similar to that shown in my prior patent, hereinbefore referred to, and for the above reason I have deemed it unnecessary to describe in detail the construction and manner of operation of the clamps, since the same will be apparent to those skilled in this art.

20 The two members will be pivoted in such a manner that the jaws will approach each other substantially in the direction of the length of one of the members. The jaw of the internal member is of greater length than the jaw of the outer member, and when the members are in clamped position the jaws will be moved in proportion to the strain upon the clamp, and the material will be clamped between the edge of the one jaw and the other plate and between the faces of the jaws, and in both embodiments the clamping-jaws will be disposed transversely to the direction of strain and relatively movable substantially in the direction of the strain.

25 As will be readily understood from Fig. 1, the entire device may be struck from sheet metal and readily formed by suitable dies. In the operation the clamps are secured along the edge of the skin or hide, as required, and the stronger the flexible connection is drawn around the fastening device therefor the more effective is the bite upon the leather, as will be apparent, and as the internal clamping members engage the leather, and the jaw 30 is being moved toward the clamping-jaw 5 of the outer member, it will be seen that the journals 8 will be forced upwardly, so that when the parts are in clamped position the top of the journals 8 will engage the upper ends of the slots 7, as seen in Figs. 2 and 4, so that there is no possibility of the hide or skin being pulled out or becoming detached. When the clamp is open, the internal member will have free play within the sides 3, and it will be apparent that by increasing or diminishing the length of the slots 7 the amount of play given to the internal member may be correspondingly increased or diminished according to the conditions and requirements 35 of the case.

Having thus described my invention, what I claim as new, and desire to secure by Letters Patent, is—

1. A clamp consisting of an external member having a jaw, and an internal member having a jaw and pivoted relatively thereto in such a manner that the jaws approach each other substantially in the direction of the length of one of the members, means for permitting the relative vertical bodily movement of the internal member at its pivot with respect to the external member, and a flexible connection engaging the two members to clamp the jaws. 70

2. A clamp consisting of an external member having an upwardly-deflected jaw and provided with sides having vertically-elongated slots therein, an internal member having a downwardly-deflected clamping-jaw, and journals adapted to be seated in said slots, means for preventing the disengagement of said journals with said slots, and a flexible connection engaging the two members to clamp the jaws. 80

3. A clamp consisting of an external member having an upwardly-deflected jaw, said member having elongated slots therein extending in substantially the same direction as said jaw, an internal member having a downwardly-deflected jaw and journals engaging said slots, lugs at the ends of said journals to prevent their disengagement from said slots, and a flexible connection engaging said members to clamp the jaws. 90

4. In a clamp, a pair of pivoted members having inwardly-directed jaws, one of which jaws lies between the other and the pivot-point and moves in a line substantially parallel to the other member and in proximity to it, means for moving one of the jaws in proportion to the strain upon the clamp and compressing the material clamped between the edge of the one jaw and the other member and between the faces of the jaws, and means for permitting the relative movement of said members bodily toward and from each other when in unclamped position. 100

5. A clamp comprising two pivoted members having jaw portions disposed transversely to the direction of strain, relatively movable substantially in the direction of strain and having extensions beyond the pivot-point, means for permitting the relative movement of said members bodily toward and from each other when in unclamped position, and a flexible connection engaging said extensions to clamp the jaws. 115

6. A clamp consisting of an external slotted member and an internal member having journals engaging said slots, said members having inwardly-directed jaws, the slots of said external member being disposed substantially parallel with its jaw, lugs at the ends of said journals to prevent their disengagement from said slots when the members are 120 130

in clamped position and to permit disengagement of said members when in unclamped position, the length of said slots being greater than the length of said lugs, and a flexible connection engaging said members to clamp the jaws.

7. A clamp comprising a member, one end of which forms a jaw which extends transversely of the length of the member and the other end of which is provided with means for engaging a flexible connection, said member having elongated slots therein substantially parallel with the jaw, and a second member journaled in said slots, one end of said second member being movable substantially in the direction of the length of the first member, the opposite end of which is provided with means for engaging the flexible connection, said second member having relative movement away from said first member during the clamping action.

8. A clamp comprising two members, each of said members having a rearward extension of different lengths in the two members and provided with an eye therein and each having a forward extension terminating in a jaw, said jaws deflecting toward each other, one of said members having elongated slots therein substantially parallel with its jaw, the other of said members having journals adapted to be seated in said slots and engage the upper ends thereof when in clamped position, means for preventing the disengagement of said journals with said slots and a flexible connection passing through the eye in said longer extension and secured at its extremity to the eye in said shorter extension.
